(57) **CLAIM**

The ornamental design for a rebar chair, as shown and described.

DESCRIPTION

FIG. 1 is a top perspective view of the chair;

FIG. 2 is a first elevational view of the chair, the opposite elevational view being a mirror image thereof;

FIG. 3 is a cross-sectional view of the chair, taken on the plane designated by line 3—3 of FIG. 2;

FIG. 4 is a top plan view of the chair;

FIG. 5 is a bottom plan view of the chair;

FIG. 6 is a second elevational view of the chair, the opposite elevational view being a mirror image thereof; and,

FIG. 7 is a third elevational view of the chair, the opposite elevational view being a mirror image thereof.
